UNITED STATES PATENT OFFICE.

EDWARD PRECHT AND VICTOR TOEPKEN, OF NEW YORK, N. Y.

IMPROVEMENT IN THE MANUFACTURE AND PACKING OF FRICTION-MATCHES.

Specification forming part of Letters Patent No. **36,967**, dated November 18, 1862; antedated May 18, 1862.

To all whom it may concern:

Be it known that we, EDWARD PRECHT and VICTOR TOEPKEN, of the city, county, and State of New York, have invented some new and useful Improvements in the Manufacture and Preparation of Friction-Matches; and we do hereby declare that the following is a full and exact description thereof, reference being had to the accompanying drawings, making part of this specification.

The first part of our invention consists in making the match-splints from thin strips of suitable wood, having about the thickness of ordinary veneer, a breadth a little greater than the required length of the splints, and any convenient length transverse to the grain of the wood. Each strip is then cut into two sets, A, B, of splints, those of each set adhering together a little distance at *a a a*, and the whole resembling a comb in appearance, substantially as represented in Figure 1. The tips *b b* of the splints are then dipped into the igniting compound, several "combs" at once.

The second part of our invention consists in packing the tips of these combs of splints alternately between the folds of a band, C, of paper, the upper edge, *c*, of which is provided with a substance that will cause the prepared tips *b b* of the matches to ignite when brought into contact therewith. We pack the matches by rolling the strips or combs of splints closely together with a band, C, of the prepared paper, the tips of the splints reaching in beyond the prepared edge *c* of the band, so as not to come in contact therewith by any accident till drawn out lengthwise, one by one, for use. The band is wound so tightly around the splints that they shall not only be held securely in it, but that no match can be drawn out without producing enough friction against the prepared edge of the band to ignite its tip. When a bunch or roll of matches of the proper size is formed, the whole is secured together by some suitable adhesive substance applied to the lower edge of the band, and by surrounding the whole with a suitable case, or in any other suitable and convenient manner. When thus packed, the matches

will be held closely enough to ignite every one in succession to the last in the act of drawing them out of the band. The igniting compound on the tips *b b* of the matches is of such a composition that it will not alone ignite by any amount of friction, and the substance on the edge *c* of the band is of a similar nature; but when the one is brought into contact with the other with a moderate degree of friction, the compound on the matches ignites with certainty and lights the match. The band C, however, will not be set on fire thereby. Any compositions or substances of suitable chemical qualities relative to each other to effect these results may be employed, and many such may be used. A suitable preparation of chlorate of potash, applied in a manner well known to those skilled in the art, will answer well to cover the match-tips with, and a similar application of amorphous phosphorus will serve for the edge of the paper band. When a match is to be lighted, it is only necessary to draw one from the package and it ignites in the act.

The convenience of the article is apparent. Each match is easily split from the comb.

The advantages derived from the method of constructing the match-splints as specified are, first, there is no loss of material, for two combs are cut at the same time out of a strip of the proper width, the two sets of "teeth" fitting into each other, as shown; second, the matches of each comb cling together, so that they are handled, dipped, and rolled in the paper band together, being placed in the right position without care or trouble, thereby avoiding the usual tedious necessity of picking up the matches one by one; third, the tips of the matches are held at a proper and uniform distance apart in packing, so that there is no danger of misplacement and accidental ignition, and in drawing out the matches from the bunch only the one drawn out can ignite.

What we claim as our invention, and desire to secure by Letters Patent, is—

1. Making the match-splints of thin strips of wood in double sets or combs, those of each comb adhering together at the upper ends,

substantially as and for the purposes herein specified.

2. Packing the tips of the matches in a band of paper, which is prepared with a composition or substance on its upper edge, whereby the match tips (correspondingly prepared) are ignited on coming in contact therewith in

the act of drawing out of the package, substantially as herein specified.

EDWARD PRECHT.
VICTOR TOEPKEN.
